UNITED STATES PATENT OFFICE.

MAURICE E. BLOOD, OF KALAMAZOO, MICHIGAN.

DESIGN FOR A BICYCLE-FRAME.

SPECIFICATION forming part of Design No. 31,051, dated June 20, 1899.

Application filed May 16, 1899. Serial No. 717,105. Term of patent 3½ years.

To all whom it may concern:

Be it known that I, MAURICE E. BLOOD, a citizen of the United States, residing at the city of Kalamazoo, in the county of Kalamazoo and State of Michigan, have invented a certain new and useful Design for Bicycle-Frames, of which the following is a specification.

This invention relates to a new and original design for bicycle-frames, of which the following is a specification, reference being had to the accompanying drawings, forming a part thereof.

Figure 1 is a perspective view of a bicycle-frame, showing my new design. Fig. 2 is an enlarged sectional view taken on line 2 2 of Fig. 1. Fig. 3 is also an enlarged sectional view taken on line 3 3 of Fig. 1, looking toward the forks in each instance.

As shown in the drawings, the leading and material features of my design consist of the

shanks B and C to the forks, which are diamond-shaped in cross-section and arranged in connection with the prongs C' and B' of the rear forks, as shown in Fig. 1 of the drawings. 25 The remaining portions of the bicycle-frame are made up of straight tubes arranged in a manner similar to bicycle-frames now in common use.

Having described my invention, what I claim as new, and desire to secure by Letters Patent, is—

The design for a bicycle-frame as herein shown and described.

In witness whereof I have hereunto set my 35 hand and seal in the presence of two witnesses.

MAURICE E. BLOOD. [L. S.]
